UNITED STATES PATENT OFFICE.

EDWARD J. SHEARER, OF COLTON, CALIFORNIA, AND MARSHALL M. OWENS, OF LORDSBURG, NEW MEXICO.

GAGE-COCK.

1,346,984.

Specification of Letters Patent.

Patented July 20, 1920.

Application filed July 18, 1919. Serial No. 311,710.

To all whom it may concern:

Be it known that we, EDWARD J. SHEARER and MARSHALL M. OWENS, citizens of the United States, residing (SHEARER) at Colton, in the county of San Bernardino and State of California, and (OWENS) at Lordsburg, in the county of Grant and State of New Mexico, have invented certain new and useful Improvements in Gage-Cocks; and we do declare the following to be a full, clear, and exact description of the invention, such as will enable others skilled in the art to which it appertains to make and use the same.

15 This invention relates to gage cocks.

One object of this invention is to generally improve upon devices of this character by providing an improved structure that comprises few, simple, strong and durable 20 parts, and is very practical and effective.

Other objects and advantages may become apparent to persons who read the following details of description in connection with the accompanying drawings, in 25 which:—

Figure 1 is a longitudinal vertical sectional view through our improved gage cock and a portion of a boiler with which it is connected.

30 Fig. 2 is a transverse sectional view along the line 2—2 of Fig. 1.

Referring to these drawings in detail, in which similar reference characters correspond with similar parts throughout the 35 several views, and in which the boiler is indicated at A,—

The invention consists in the general construction and combination in which a boiler connection 3 is formed with an internally 40 threaded chamber 4 and a passage or port 5 through which water flows from the boiler. A valve body 6 is formed with an externally threaded portion 7 by means of which it is secured in the chamber 4, and the element 7 co-acts with the chamber 4 to form 45 a valve housing in which the closing element or head 8 of a valve 9 is movable to opening and closing relation with a valve-seat 10 formed in the end of the element 7. The valve body 6 is also formed with a 50 valve-seat 11, an outlet or drain pipe 12, a valve-bearing 13, and a packing seat 14. A nut 15 holds the packing in the seat 14 and is provided with internal threads 16 55 which engage with external threads 17 of a

main valve member 18. The main valve member is provided with an actuating handle or wheel 19 and with an internal abutment 20. The main valve 18 is movable to and from the main valve-seat 11 by turning 60 the wheel 19, in the usual manner, and as this main valve member moves outward it effects an opening at 11 so as to permit water to flow through the port 5, chamber 4 and valve-seat 11 through the medium of 65 passages 21 which are more clearly shown in Fig. 2. In this connection, it will be seen that the stem portion of the valve 9 is slabbed or cut away at three sides, as indicated at 22, so that only three edges 23 are 70 in contact with the inner surface of the bore or hollow which connects the main valve-seat 11 with the supplemental valve-seat 10. It will be seen that the cut-away portions 22 extend into a longitudinal bore 24 in the 75 valve 18 which terminates at the abutment 20, the remaining portion of the valve 9 being cylindrical and having a smooth and easy-working fit in the cylindrical seat 24. It will be seen, therefore, that when the main 80 valve 18 is in its closing position, the supplemental valve is open to its fullest extent, being held open by means of the shoulder or abutment 20 which resists the tendency of the water and steam pressure to close the 85 supplemental valve. However, when the valve 18 is moved away from the valve seat 11, beyond a predetermined extent, or when the cap 15 is removed, the supplemental valve is immediately closed by the 90 water and steam pressure, so that the water and steam cannot escape, and the main valve 11 may be reground, or the valve body repacked, without danger to the operator.

Although we have described this embodiment of our invention very specifically, it is not intended to limit the same to these exact details of construction and arrangement, but appropriate changes may be made without departing from the inventive idea 95 as described and claimed.

What we claim as our invention is:

A gage cock comprising a boiler connection having an internally threaded chamber therein, a one-piece valve body including an 100 externally threaded inner end and an externally threaded outer end, said inner end being fitted in said chamber and combining therewith to form a valve-housing, said valve body also including a main valve seat, 110

a supplemental valve seat and a passage, this passage connecting the main valve seat with the supplemental valve seat, said valve body also including a water outlet and a 5 valve bearing in communication with said main valve seat, a main valve in said valve bearing, this main valve being tubular and cylindrical from its inner end to a portion adjacent to its outer end, this outer end 10 portion having a handle thereon and an externally screw threaded portion between said handle and the cylindrical portion of the main valve, the hollow of this tubular valve terminating in an abutment, a nut in 15 threaded engagement with the outer end of said one-piece valve body, said main valve having screw threaded engagement with said nut and thereby being longitudinally movable to and from said main valve seat, 20 and a one-piece supplemental valve includ-

ing a head and a stem, said stem being straight and having all its parts of substantially equal lateral extent, this stem extending through said passage and through the hollow of said main valve and normally 25 abutting against said abutment so that the latter normally holds said supplemental valve out of the supplemental valve-seat, but permits the supplemental valve to close when said main valve is opened a predetermined extent, said valve stem being longitudinally 30 slideable in the tubular portion of said main valve to permit the latter to move longitudinally from its closing position after the said supplemental valve has closed and ceased to 35 move.

In testimony whereof we have hereunto set our hands.

EDWARD J. SHEARER.
MARSHALL M. OWENS.
